224,607

AIRCRAFT

T. Desmond Earl, Buffalo, N.Y., assignor to
Textron Inc., Providence, R.I.

Filed Aug. 31, 1970, Ser. No. 24,764

Term of patent 14 years

Int. Cl. D12—07

U.S. Cl. D71—1

FIG. 1 is a bottom-side perspective view of an aircraft showing my new design;

FIG. 2 is a top plan view thereof;

FIG. 3 is a side elevational view thereof; and

FIG. 4 is a front elevational view thereof.

The appearance of the aircraft of the design is substantially the same when viewed from opposite sides thereof.

I claim:

The ornamental design of an aircraft, substantially as shown and described.
